FIG. 1 is a front perspective view of the multi-functional foldable car seat;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof;

FIG. 8 is a front view of the multi-functional foldable car seat in a flat position;

FIG. 9 is a back view thereof;

FIG. 10 is a left view thereof;

FIG. 11 is a right view thereof;

FIG. 12 is a top view thereof;

FIG. 13 is a bottom view thereof;

FIG. 14 is a front view of the multi-functional foldable car seat in a folded position;

FIG. 15 is a back view thereof;

FIG. 16 is a left view thereof;

FIG. 17 is a right view thereof;

FIG. 18 is a top view thereof; and,

FIG. 19 is a bottom view thereof.
